UNITED STATES PATENT OFFICE.

ALBERT ZETTER, OF FREEBURG, ILLINOIS.

DEVICE FOR USE IN EXTRACTING RAILROAD-TIES OR THE LIKE.

SPECIFICATION forming part of Letters Patent No. 623,300, dated April 18, 1899.

Application filed November 28, 1898. Serial No. 697,640. (No model.)

To all whom it may concern:

Be it known that I, ALBERT ZETTER, a citizen of the United States, residing at Freeburg, in the county of St. Clair and State of Illinois, have invented certain new and useful Improvements in Devices for Use in Extracting Railroad-Ties or the Like; and I do hereby declare the following to be a full, clear, and exact description of the invention, such as will enable others skilled in the art to which it appertains to make and use the same.

My invention relates to improvements in devices for use in extracting railroad-ties and the like of that general class shown in Patents No. 317,829, dated May 12, 1885, and No. 561,352, dated June 2, 1896, which patents are hereby acknowledged and have been borne in mind in the preparation of this application; and the invention has for its object to so construct the device as to greatly strengthen the same and make it more efficient in operation.

The invention is embodied in the peculiar arrangement and combination of parts, as more fully hereinafter described, and specifically pointed out in the claims.

In the drawings I have shown one embodiment of the invention; but it is to be understood that it is not intended to be limited in the future interpretation of this application to such particular construction, which for the mere sake of illustration is herein delineated.

In said drawings, Figure 1 is a plan view of the construction in operative position, a section of track being shown in dotted lines. Fig. 2 is a side view of the same, the track being shown in cross-section. Fig. 3 is a sectional view on the line $x-x$ of Fig. 2, and Fig. 4 is a detail plan view of the double rack-bar and its securing means for the tie.

Referring to the drawings, wherein like reference characters designate corresponding parts in the several views, A represents a section of track, and B the ties thereof.

C is a bracket having at its upper end integral or suitably secured thereto a handle or lever D and at its lower end an elongated opening E. To the respective sides of the bracket, occupying a position substantially in the plane of the center of the opening therein, are outwardly-projecting pins e and e'. Pivoted at their outer ends to these pins are relatively short brace-rods F and F', having

recessed or cut-out portions f and f' at their inner ends, adapted when the device is in operative position to bear against the near rail of the section of track.

G represents a relatively long bracing-rod having at its inner end a cut-out portion g, corresponding to the recesses ff' of the short rods and adapted to bear against the far rail of the track. Intermediate its ends this rod G has a notched portion g' in its lower end, also adapted to embrace the near rail of the track mid-distance between the bearing-points of the short rods. From this notched portion outward the rod G is arched and terminates in the fork H. The diverging branches h h' of the fork are turned downward at their extreme ends and are then in turn pivoted to the pins e e', respectively.

Pivoted between the side walls of the bracket, near the upper and lower ends of the opening therein, are two pawls J J', their points projecting outwardly, as best seen in Fig. 2. The lower pawl J' is somewhat heavier at its rear or enlarged end than at its pointed end, so that the latter will be constantly held up in engagement with the ratchet-bar.

Adapted to work through the opening in the bracket and be engaged by the pawls J and J' is an elongated draw-bar K. Throughout the greater extent of this bar, on its upper and lower surfaces, are a series of teeth or depressions k k', arranged slightly out of alignment with each other. At the inner end of the bar is means for securing the same to a tie, and suitable means for this purpose is embodied in the following construction: The inner portion of the draw-bar K is bifurcated and has the diverging arms l l', the ends of which are united and held in their normal condition by the cross-bar L.

Wedge-shaped blocks M M' are arranged to slidingly engage the arms l and l' through the medium of attaching-links N N', preferably two being employed for each block. On the inner face of each block are biting projections or teeth O, adapted to embed in the sides of the tie when in operative position.

In order to provide a varying grip to accommodate different-sized ties and also to cause the wedge-blocks to approach each other and bind a tie when the same is placed therebetween and tension applied when with-

drawing, I make use of an adjusting-screw P, (or one for each block may be employed, if desired.) It will thus be seen that when a tie is placed between the blocks with their binding-teeth primarily engaging the sides of the same subsequently when the device is manipulated the outward pull on the draw-bar and in turn the blocks will cause the blocks to approach each other by reason of the adjusting screw or screws and the opposite pull of the tie, and thus firmly clamp the tie.

In case a tie be somewhat loose and a lighter grip therefore desired, I flexibly connect to the draw-bar at about its center a grapple Z, of any ordinary construction, which when used will be adapted to grasp the end of a tie.

From the foregoing description the operation will be apparent. The device is placed in the position clearly shown by Figs. 1 and 2, with the brace-rods F, F', and G bearing against the respective rails of the track. The clamp at the end of the draw-bar K is applied to the tie desired to be extracted, and then the handle or lever D is worked to and fro, thereby rocking the bracket on its pivots e e', and consequently imparting to the pawls in the bracket an alternating movement, whereby the teeth of the draw-bar are engaged by the latter and the bar itself, together with the tie, drawn outward by a step-by-step movement.

It is desired to be understood that wherever the word "tie" is employed in the specification and claims herein it is with the idea that the term is broad enough not only to comprehend ties themselves, but all other things to which the device is applicable or may be applied.

40 Should it be desired to shove the tie out from under the rails of the tracks instead of pulling out the same; I reverse the whole device, so that the square end of the rack-bar will bear against the end of a tie, and make use of the hooked stay-rods W, (shown by the dotted lines in Fig. 2,) the hooked ends of said rods being adapted to catch underneath the near rail. In this manner when the bracket and its mechanism are operated 45 50 the rack-bar instead of pulling on the tie, as described in the first instance, will work in an opposite direction and shove the tie out at the opposite side of the track.

Having thus described the invention, what is claimed as new, and desired to be secured by Letters Patent, is—

1. In a tie-extractor, the combination with a bracket and means for operating the bracket, independent relatively long and short stay-rods each pivoted to said bracket and having portions adapted to engage with the rails of a track, and a draw-bar operated by said bracket, substantially as described.

2. In a tie-extractor, the combination with a bracket and means for operating the bracket, relatively long and short stay-rods for retaining it in position relative to the rails of a track

pawls mounted in said bracket, and a draw-bar passing through the bracket and adapted to be connected to a tie and be engaged by 70 said pawls when the bracket is manipulated, substantially as described.

3. In a tie-extractor, the combination with an oscillatory bracket and means for operating the same, relatively long and short 75 brace-rods pivoted to said bracket, pawls mounted in said bracket, and a draw-bar adapted to be connected to a tie and engaged by said pawls when the bracket is operated, substantially as described. 80

4. In a tie-extractor, the combination with mechanism for attaching and withdrawing a tie, relatively short brace-rods secured to said mechanism and adapted to bear against one rail of a track, and a relatively long brace-rod adapted to bear against the opposite rail, substantially as described. 85

5. In a tie-extractor, the combination with mechanism for attaching and withdrawing a tie, relatively short and long brace-rods secured to said mechanism and adapted to bear against the respective ties of a track, substantially as described. 90

6. In a tie-extractor, the combination with mechanism for attaching and withdrawing a tie, relatively short brace-rods secured to said mechanism having engaging portions for one rail of a track and a relatively long brace-rod also secured to said mechanism and having an engaging portion for the opposite rail of 95 a track and additional means for engaging the same rail as the short rods, substantially as described. 100

7. In a tie-extractor, the combination with a bracket and means for operating the same, 105 having an elongated opening therein, pawls pivoted in said opening, a toothed bar passing through said opening and adapted to be engaged by the pawls, and a clamp at the end of the bar for securing it to a tie, substantially as described. 110

8. In a tie-extractor, the combination with a pawl-and-ratchet mechanism for attaching and withdrawing a tie, and relatively long and short brace-rods having portions adapted 115 to engage the respective rails of a track when the same is being operated, substantially as described.

9. In a tie-extractor, the combination with a bracket having an elongated opening therein, pawls pivoted in said opening, a toothed bar passing through said opening and adapted to be engaged by the pawls, means at the end of the bar for securing it to a tie, and relatively short and long brace-rods pivoted to 120 the sides of the bracket, substantially as described.

10. In a tie-extractor, the combination with mechanism for attaching and withdrawing a tie, relatively short brace-rods secured to said 125 mechanism and adapted to bear against one rail of a track, and a relatively long brace-rod also secured to said mechanism and adapted to bear against the opposite rail of a track 130

at a point intermediate the bearing-points of the short rods, substantially as described.

11. In a tie-extractor, the combination with a bracket, mechanism in said bracket for attaching and withdrawing a tie, relatively short brace-rods pivoted to the respective sides of said bracket, and a relatively long brace-rod having a forked pivoted portion, and adapted to occupy a position centrally 10 of the short rods, substantially as described.

12. In a tie-extractor, the combination with a draw-bar bifurcated at one end, means for operating said bar, and gripping members secured in the bifurcated portion thereof, substantially as described.

13. In a tie-extractor, the combination with a bracket and operating means therefor having a vertical elongated opening therein, mechanism therein for withdrawing a tie comprising a toothed draw-bar having a separated portion at one end, means for operating the bar, and a clamp in the separated portion of the draw-bar for attachment to a tie, substantially as described.

14. In a tie-extractor, the combination with a draw-bar bifurcated at one end, means for operating said bar, wedge-shaped blocks slidably engaging the arms of the bifurcated portion and adapted to clamp a tie, substantially as described.

15. In a tie-extractor, the combination with a draw-bar, means for operating said bar, and wedge-shaped blocks mounted at one end of the bar and adapted to clamp a tie, substantially as described.

16. In a tie-extractor, the combination with a draw-bar, means for operating said bar, wedge-shaped blocks mounted at one end of the bar, and adjusting means for said blocks, substantially as described.

17. In a tie-extractor, the combination with a draw-bar, means for operating said bar, and toothed wedge-shaped blocks mounted at one end of the bar and adapted to clamp a tie, substantially as described.

18. In a tie-extractor, the combination with a draw-bar, means for operating said bar, blocks mounted at one end of the jaw and adapted to grip a tie, and an adjusting-screw for said blocks, substantially as described.

19. In a tie-extractor, the combination with a draw-bar bifurcated at one end, means for operating said bar, gripping members slidably engaging the arms of the bifurcated portion, and a cross-bar uniting and bracing the ends 55 of the said arms, substantially as described.

20. In a railroad-tie extractor, the combination with tie-moving instrumentalities, and alternating sets of stay-rods extended in opposite directions for retaining the same in reversed positions relative to the rails of a track; substantially as described.

21. In a railroad-tie extractor, the combination with tie-moving instrumentalities, and relatively long and short recessed brace-rods 65 for retaining the same in position relative to both rails of a track, substantially as described.

22. In a railroad-tie extractor, the combination with tie-moving instrumentalities, two 70 series of stay-rods for retaining the same in alternate positions relative to the rails of a track, and hooks on one series of said rods, substantially as described.

In testimony whereof I affix my signature 75 in presence of two witnesses.

ALBERT ZETTER.
